J. C. Smith

Riding-Saddle Tree

N° 8,064.

Patented Apr. 29, 1851.

UNITED STATES PATENT OFFICE.

J. C. SMITH, OF STOUGHTSTOWN, PENNSYLVANIA.

SPRING-SADDLE.

Specification of Letters Patent No. 8,064, dated April 29, 1851.

To all whom it may concern:

Be it known that I, JOSEPH C. SMITH, of Stoughtstown, in the county of Cumberland and State of Pennsylvania, have invented a new and useful Improvement in Spring Saddletrees, of which the following is a full, clear, and exact description, reference being had to the accompanying drawing, which forms part of this specification and represents a view in perspective of my bridge-spring saddletree.

My invention consists in mounting upon the saddle tree a series of spring plates which cross it transversely and bridge the opening between the side pieces, these bridge springs being all connected by a spring plate which extends longitudinally from the pommel toward the cantle and is connected with the former by a spring which allows it to yield as the bridge springs are depressed by the weight of the rider.

In the accompanying drawing A, A, are the side-pieces of the saddle tree which are connected in the usual manner by the pommel B and cantle C. A series of transverse, arched spring plates *a* are mounted upon the side pieces, and bridge the opening between them. The extremities of these bridge springs rest upon metal plates *b* secured to the side pieces, to which they are attached by screws *c* which pass through slots *e* in the extremities of the bridge springs *a* and retain them in their proper position upon the saddle tree. The extremities of one of these bridge springs are prolonged and are fitted with links *f* to which the stirrup leathers are secured.

The bridge spring plates are all connected at their middles with a longitudinal plate *d* which extends from the pommel B toward the cantle C. This longitudinal plate is connected with the pommel by a spiral spring *g* which yields as the bridge springs are depressed and contracts as they rise, thus allowing the longitudinal plates *d* to move as the extremities of the bridge springs slide down upon the side plates *b*. The leather cushion which forms the seat is mounted upon this spring bridge frame and the stirrup leathers are suspended from the

links *f* at the prolonged extremities of one of the bridge plates.

This method of constructing spring saddle trees affords an easy and comfortable seat to the rider, who being supported on a spring frame is relieved from the unpleasant jolting motion caused by a heavy footed riding horse. The yielding connection of the longitudinal plate with the pommel is of considerable importance in reference to the comfort of the rider, for if the connection was unelastic, the highest parts of the bridge springs would be drawn forward as they were depressed, thus communicating a very uneasy movement to the seat of the saddle; whereas by this construction the bridge springs are allowed to move slightly backward, thus accommodating themselves to the natural movement of the rider. The seat of the rider is rendered more easy and comfortable by the action of the stirrups which are suspended from the spring frame and yield with it, by which means the distance between the seat and stirrups is kept constantly the same, whether the former is raised or depressed by the action of the springs; thus a saddle is formed by means of which the whole weight of the rider is constantly sustained upon springs which, while they add to the comfort of the rider, relieve the horse to a great extent from the jolts and working of the saddle caused by bad riding.

Having thus described my bridge-spring saddle tree what I claim therein as new and desire to secure by Letters Patent is—

1. The pommel spring in combination with the seat springs substantially as herein set forth.

2. I also claim the method of suspending the stirrups by connecting them with the same springs which support the seat, whereby the elevation and depression of the one is simultaneous with the elevation and depression of the other.

In testimony whereof I have hereunto subscribed my name.

JOSEPH C. SMITH.
